MAGNET SYSTEM WITH MOVABLE COIL

Jan Wouda, Vechten, near Utrecht, Netherlands, assignor to N. V. Nederlandsche Instrumenten- en Electrische Apparaten-Fabriek "Nieaf," Utrecht, Netherlands, a company of the Netherlands

Application June 17, 1952, Serial No. 293,917

Claims priority, application Netherlands June 22, 1951

5 Claims. (Cl. 324—151)

The invention is concerned with a magnet system for electrical measuring instruments, relays, and the like, with a movable coil and a permanent magnet of ferromagnetic material with high coercive force and particularly of the type in which the coil, through the interaction of the field produced by the current in the coil and the field of the permanent magnet, is deflected about a cylindrical core of permanent-magnetic material whose magnetic flux is closed back by a structure of soft iron which leaves a narrow air gap between the core and said structure through which gap the coil moves.

More particularly, the invention is concerned with a novel arrangement of the ferromagnetic parts of the magnet system relatively to the coil such that the magnetic circuit is built up with a leakage as small as possible and for highest efficiency and fullest utilization of the magnetic energy of the system. This is achieved when, in accordance with the invention, the core of the permanent-magnetic material is in form of a flat, generally circular disc, that is a disc of a diameter exceeding the height dimension of the disc. The disc is permanently magnetized diametrically. The magnetic return path for closing back the magnetic flux of the core is constituted by a plate or a pair of plates of magnetizable soft iron disposed opposite and extended over one, or each plate over one, of the end faces of the disc, parallel thereto and spaced apart therefrom so as to leave a narrow air gap or narrow air gaps therebetween, for the passage of the magnetic flux, produced by the core, in the axial direction of the disc. A rotatable coil with means for suspending it is disposed at the magnet system with the axis of suspension and rotation coaxial with the disc. The coil is extended with one of its legs or both legs through the air gap or air gaps, the legs thus crossing the axis and the flux.

Through this structure the coil is and remains removable from the magnetic system and may be replaced without the necessity of detaching any part of the magnetic system. This system, therefore, once magnetized to produce its permanent magnetism need not be magnetized again when the coil had been removed and replaced.

Since during this operation the magnetic circuit remains unaffected, no loss of magnetization nor any diminishing of the flux from its original intensity, thus no change of the adjustment of the instrument will be experienced.

The air gap or gaps within which the leg or legs of the coil are subjected to the deflecting forces through the interaction of the fields thus cross the axis of suspension of the coil in contrast with conventional structure where the magnetic air gap within which the legs of the coil are subjected to the deflecting forces and thus move surrounds peripherally the core magnet.

For further explanation of the invention and for its illustration, various of its embodiments will now be set forth in the ensuing specification and will be illustrated in and by the accompanying drawings which are to be

2

understood illustrative of the invention and not limitative of its scope. Other embodiments incorporating the principle underlying my invention are feasible without departing from the spirit and ambit of my appended claims.

In the drawings:

Figs. 1 and 2 respectively are a rather diagrammatic plane view and an elevational view of an embodiment of the magnet system of the invention illustrating the principle thereof;

Fig. 3 is a plan view illustrating the mode in which the system is diametrically magnetized;

Figs. 4 and 5, 6 and 7, 8 and 9, and 10 and 11, are respectively plan views and elevational views of various embodiments of the invention.

Figs. 1 and 2 illustrate the principle of the invention. 11 designates the core, in the example illustrated, in the form of a flat, circular disc of permanent-magnetic material. The magnetic flux is closed back by ferromagnetic pieces 12, 13, in the form of plates of soft iron disposed in juxtaposition to the core or disc 11 at both faces thereof and leaving a narrow gap 14, 15 respectively, at each of the faces of the core between core and plate.

25 The moving coil, designated by 16, is suspended by means of its axle arms 17, 18, between appropriate bearings 19, 20, as conventional in the art. Slots 24 are provided in the plates 12, 13, and extended radially outwards so that the axles 17, 18, may be passed through and along these slots when the coil is to be removed from the magnet system or is to be replaced.

Although two ferromagnetic plates 12, 13 are shown in Figs. 1 and 2, one of these plates may be omitted without departing from the principle of the invention.

35 Fig. 3 illustrates how the core magnet of Figs. 1 and 2 may be magnetized. Two pole shoes 25, 26, of soft iron are applied to the sides of the core magnet 11, whereupon, for instance by means of a strong electromagnet, not shown in Fig. 3, a flux of such strength is sent through the core 11 that it will be saturated. After removal of the pole shoes 25, 26, the magnetic lines of force will have approximately the course as shown in Fig. 2 by dash lines with arrows.

In Figs. 4 and 5 a structural embodiment of a magnet system of the invention is illustrated. It should be noticed, however, that in order to show more clearly the essential features of the invention there have been omitted from the showing of Figs. 4 to 11 all details not essential for the illustration of the invention, details as such which may serve for the mounting or securing of the various parts, bearings, screws, spiral springs, or the like.

In these embodiments, the plates 12, 13 of soft iron are joined together by means of studs or spacers 29, 30.

55 Between the soft iron plates 12, 13, and the core magnet 11, there may be provided spacing discs 31 of non-magnetic material, brass for instance, of such shape that movement of the moving coil is not impeded while nevertheless they present contact faces as large as possible. By means of these spacing discs 31 the core magnet 11 will be secured in spaced relationship between the soft iron plates 12, 13, by clamping, soldering or brazing, cementing, or otherwise. When a proper opening or bore is provided in the core magnet, a rivet or screw may also be employed for joining the parts together.

60 In Figs. 6 and 7, in order to control the configuration of the magnetic field, the core magnet 11 is provided at its faces with pole shoes 34, 35, and 36, 37, respectively, of soft iron projecting into the air gaps 14, 15.

65 Through this means the torque which is operative on

the coil in any of its positions may be predetermined at will so that the character of calibration of the scale of the instrument may be adapted to prevailing requirements. In this way, a calibration of the scale of proportional character may be obtained.

Another possibility of attaining this result is illustrated in Figs. 8 and 9. In this embodiment the circumference of the core magnet 38 is not of circular contour but deviates therefrom. The deviation may be an elongation of the contour in one direction such as for instance transversely of the direction of magnetization. In this way too the character of the scale graduation may be modified. The form of the core disc 38 as illustrated results in a nearly proportional graduation of the scale. By selection of any other shape, the graduation of the scale may, within certain limits, be chosen at will.

It is also possible to control the configuration of the flux by shaping the soft iron plates appropriately. An embodiment illustrating this feature is shown in Figs. 10 and 11 where pole shoes 41, 42, and 43, 44, respectively projecting into the air gaps are provided at the soft iron plates 12, 13, on the surfaces thereof which face the air gaps. The shape of these pole shoes may be chosen as desired. The same purpose may be achieved by providing for an appropriate form of the soft iron plates themselves instead of providing them with pole shoes, or additionally thereto.

In all embodiments shown it is also possible to control the configuration of the lines of force by selecting an appropriate direction or axis of magnetization, for instance by applying in the magnetizing arrangement of Fig. 3 the pole shoes 25, 26, to the core magnet 11 in another direction or position than that illustrated.

It is also possible to employ a core not totally of permanent-magnetic material but to employ such material for instance only for the central part of the core and make the remaining part or parts of soft iron.

The invention is also applicable in instruments where several permanent-magnetic cores and several coils, more than one of each, are employed.

In any case the coil may be readily removed and replaced without any interference of the structure of the magnet system.

What I claim is:

1. A magnet system for use in electrical measuring instruments, relays and the like, comprising a core of permanently magnetized material shaped in the form of a substantially circular disc having two parallel faces, said core being magnetized across its diameter, said disc having a diameter exceeding the height dimension thereof, a magnetic flux carrying member comprising at least one plate of ferro-magnetic material disposed opposite one of said core faces in spaced, parallel relationship thereto and forming a narrow air gap for the passage of magnetic flux produced by said core in a direction generally parallel to the central axis perpendicular to the face of said core, said plate being at least as wide as the face of said core adjacent thereto, a rotatable coil disposed around said core, means for rotatably mounting said coil with its axis of rotation coaxial with said axis of the core, said coil being arranged in said air gap and around said core, said coil being adapted to be connected to an electrical circuit and to be rotated by the interaction of the current in said coil with said flux uniformly over a wide arc about the circumferential face of said core, and said plate being provided with a slot extending radially outwardly from its center to permit the removal and replacement of said coil without disturbing the structural and magnetic relationship of the core and said plate.

2. A magnet system as described in claim 1, and in-

cluding pole shoes mounted on said plate and with said shoes protruding into said air gap.

3. A magnet system as described in claim 1, further comprising two plates and having pole shoes mounted on each of said plates and said pole shoes protruding into said air gap.

4. A magnet system for use in electrical measuring instruments, relays and the like, comprising a core of permanently magnetized material in the form of a substantially circular disc of a diameter exceeding the height dimension thereof, said core having two substantially flat faces parallel to each other, said core being permanently magnetized across the diameter, a magnetic return path for carrying the flux of said core which comprises two plates of ferro-magnetic material each disposed opposite one of said core faces in spaced parallel relationship thereto and forming a narrow air gap with said core for the passage of the magnetic flux produced by said core in a direction substantially parallel to the central axis perpendicular to the face of said core, each of said plates being at least as wide as the circular core face opposed thereto, a rotatable coil arranged around said core, means for rotatably mounting said coil with its axis of rotation coaxial with said axis of said core, said coil having a side extending through each of said air gaps, said coil being adapted to be connected to an electric circuit and to be rotated by the interaction of the current in said coil with said flux uniformly over a wide arc about the circumference of said circular core, and non-magnetic spacing means disposed between said core and said plates for maintaining the same in a fixed spaced relationship.

5. A magnet system for use in electrical measuring instruments, relays and the like, comprising a core of permanently magnetized material in the form of a substantially circular disc of a diameter exceeding the height dimension thereof, said core having two substantially flat faces parallel to each other, said core being permanently magnetized across the diameter, a magnetic return path for carrying the flux of said core, said magnetic return path comprising two plates of ferro-magnetic material each disposed opposite one of said core faces in spaced parallel relationship thereto and forming a narrow air gap with said core for the passage of magnetic flux produced by said core in a direction substantially parallel to the central axis perpendicular to the face of said core, each of said plates being at least as wide as the circular core face opposed thereto, a rotatable coil disposed around said core, means for rotatably mounting said coil with its axis of rotation coaxial with said axis of said core, said coil having a side extending through each of said air gaps, said coil being adapted to be connected to an electric circuit and to be rotated by the interaction of the current in said coil with said flux uniformly over a wide arc about the circumference of said circular core, and each of said plates being provided with a slot extended radially outwardly from its center whereby removal and replacement of said coil without disturbing the structural and magnetic relationships of said core and said plates is facilitated.
